(57) CLAIM

The ornamental design for a universal holder for decorative articles, as shown and described.

DESCRIPTION

FIG. 1 is a front elevational view of a universal holder for decorative articles showing my new design;

FIG. 2 is a rear elevational view thereof;

FIG. 3 is a top plan view thereof;

FIG. 4 is a bottom plan view thereof;

FIG. 5 is left side elevational view thereof; and,

FIG. 6 is right side elevational view thereof.

The broken lines, showing candle receptacles and mounting hardware there of represent environmental structure and form no part of the claimed design.
